UNITED STATES PATENT OFFICE.

JOEL COUCH, OF CLAYTON, NEW YORK.

CENTER-BOARD FOR VESSELS.

SPECIFICATION forming part of Letters Patent No. 448,503, dated March 17, 1891.

Application filed October 30, 1890. Serial No. 369,829. (No model.)

To all whom it may concern:

Be it known that I, JOEL COUCH, a citizen of the United States of America, residing at Clayton, in the county of Jefferson and State 5 of New York, have invented certain new and useful Improvements in Center-Boards for Vessels; and I do hereby declare the following to be a full, clear, and exact description of the invention, such as will enable 10 others skilled in the art to which it appertains to make and use the same, reference being had to the accompanying drawings, and to letters of reference marked thereon, which form a part of this specification.

15 This invention relates to improvements in center-boards for vessels or canoes.

The object of the invention is to provide a folding center-board made up of braces or hangers to which are pivotally connected the 20 blades so as to position the braces or hangers at an angle with the keel while the blades lie parallel therewith, the construction being such that the blades and hangers can be elevated or depressed by operating a lever connected with 25 the forward hanger to extend within the vessel; and it consists in the construction and combination of the parts, as will be hereinafter fully set forth, and particularly pointed out in the claims.

30 In the accompanying drawings, forming part of this specification, Figure 1 is a side view of a center-board, showing the same applied to a vessel. Fig. 2 is a sectional view.

A refers to a box or housing, which is adapted to be secured over an opening in the keel of the vessel and inclose the center-board when the same is raised. Near the forward end of this box or housing are located bearings for a pin, which support the main hanger B, both of 35 said bearings being open and provided with a packing to permit one end of the pin to project within the vessel for attachment thereto of an operating-lever. The supporting-pin is rigidly connected to the hanger by having a 40 squared portion, which engages with a corresponding perforation in the hanger. The rear portion of the box at its upper edge is slightly raised above its normal plane to receive a supplemental hanger D, the upper end of said 45 hanger being provided with a slot through which a connecting-pin d passes. The front

hanger or brace B is perfectly flat on one side, and on the other side has a series of depressions corresponding with the number of blades employed, within which said blades are pivoted to fold one upon the other when closed. These depressions can be formed by constructing the hanger B of several sheets of metal, and rule-joints may be employed by providing the shoulders e and f. Any number of blades E 55 may be used, and it is obvious that as the hanger B swings upon its pivot each succeeding blade will have to be shorter than the one above to permit of its entering the housing. When the center-board is raised within the 60 box or housing, the blades will fold one upon the other and present a compact appearance. The supplemental hanger or brace D is pivoted to the upper blade and at its lower end to the adjacent blade, and short hangers or 65 flat strips D' connect the succeeding blades. When it is desired to lower the center-board, the lever is turned so that the front hanger will be depressed, which will carry with it the blades and supplemental hangers, the rear 70 hanger or brace D, having a slotted connection, permits the same to swing down and present its enlarged portion d' within the box 75 snugly between the side walls thereof, so as to provide a rigid support. A board thus constructed is extremely rigid.

I am aware that prior to my invention it has been proposed to construct a center-board of blades pivoted upon a common bolt and adapted to be operated by a lever located 85 within the vessel, said blades being adapted to be used in connection with a box attached above or to the keel or keelson of a vessel, also that center-boards have been made up of blades pivoted to hangers and 90 adapted to fold against the bottom of the vessel, so that the blades will lie alongside each other, said construction being adapted to operate in one direction by gravity and in the other by a flexible connection which passes 95 around the vessel.

Having thus described my invention, what I claim as new, and desire to secure by Letters Patent, is—

1. In a center-board for vessels, the combination, with a box adapted to receive the center-board, of a front hanger secured to the box 100

by a pin which turns therein, so as to provide means for elevating and depressing said front hanger, and supplemental hangers or braces D and D', connecting the rear portions of the 5 blades to each other and to the box, substantially as set forth.

2. In a center-board for vessels, the combination of a forward hanger having a series of depressions or side recesses, horizontal blades 10 pivoted at their forward ends within said recesses so that they will lie side by side when folded, and hangers pivoted to the rear portion of the blades so as to connect the blades to each other, and a supplemental hanger or 15 brace D, movably secured to the box or well, substantially as set forth.

3. The combination, in a center-board for vessels, of a box or housing, blades E E, adapted to lie within the same when raised and be 20 projected horizontally therefrom when lowered, and hangers B and D, connecting said blades with the box, the forward hanger being secured to the box upon a turning pin, the upper portion of the rear hanger being slotted

for engagement with a stationary pin carried 25 by the box, substantially as set forth.

4. In a center-board for vessels, the combination, with a box or housing A, of a main hanger B, having depressions within which the blades are pivoted, presenting shoulders 30 e, against which shoulders f, formed on said blades, abut, substantially as set forth.

5. The combination, in a center-board for vessels, of a box A, supporting a hanger to which the blades are pivotally attached, together with a supplemental hanger or brace D, pivoted to the blades and to the housing, and presenting on one edge an enlarged portion or web which fits snugly between the side walls of the box to present a rigid support, substantially as set forth.

In testimony whereof I affix my signature in presence of two witnesses.

JOEL COUCH.
